UNITED STATES PATENT OFFICE

1,986,578

STRIPE ATTACHMENT FOR KNITTING MACHINES

Kenneth Howie, Norristown, Pa., assignor to Wildman Mfg. Co., Norristown, Pa., a corporation of Pennsylvania

Application April 29, 1932, Serial No. 608,314
Renewed March 7, 1934

8 Claims. (Cl. 66—127)

This invention is for the purpose, primarily, of producing striped effects in full fashioned stockings. The mechanism is designed more particularly as an attachment to the type of full fashioned machine disclosed in an application for Letters Patent of the United States, filed by Kenneth Howie and Charles C. Kriebel, Ser. No. 590,942, dated Feb. 4, 1932, Full fashioned knitting machine.

10 In the drawings

Fig. 1 is a vertical sectional view of a machine of the type shown in the above mentioned application with the striping attachment incorporated therein.

15 Fig. 2 is a diagrammatic plan view of a part of the full fashioned machine with the striping mechanism in place thereon.

Fig. 3 is a detail sectional view of the improvement.

20 Fig. 4 is an enlarged view of part of Fig. 3.

Fig. 5 is a front view of a part of mechanism.

Fig. 6 is a detail side view of part of the pattern mechanism.

25 Fig. 7 is a plan view of part of Fig. 5, partly in section.

Fig. 8 is a detail plan view.

Fig. 9 is a detail rear view of part of the mechanism.

Fig. 10 is a detail view.

30 Fig. 11 is a plan view of a detail.

Fig. 12 is a view of the series of cams and discs at the left hand end of the yarn changer shaft.

35 Fig. 13 is a view of the series of cams and discs belonging to the right hand end of the yarn changer shaft.

Fig. 14 is a detail view partly in section looking from the rear of the machine showing the driver for selectively operating the yarn carrier bands.

40 Fig. 15 is a detail view of Fig. 14.

Fig. 16 is a detail view of means for operating the yarn change cam shaft.

In the machine of the application above mentioned a series of yarn directing eyes or guides 45 are mounted on endless carriers designated as a group 26 and consisting each of a thin steel band set up on edge and having reciprocating movement along the needle row indicated at *n* as in Fig. 2. These endless carriers individually are marked #1, #2, #3, #4, #5, #6 and #7 and the yarn guide eyes belonging thereto are marked 50 1 to 7.

The carriers along the forward stretch thereof are arranged close together so that each may 55 reciprocate close to the needle row. The rear

stretches of these endless carriers are more widely separated. They carry dogs 34 see Figs. 14 and 15 to be engaged by a driver like that disclosed in said application indicated generally at 31, Fig. 2 and in some detail in Figs. 14 and 15. This driver reciprocates lengthwise of and below the rear widely separated stretches of the yarn guide carrier bands. This driver carries means for selectively engaging the dogs 34 and moving the carriers according to a prescribed plan of selection to feed the proper one of the several yarns to the needles according to the particular portion of the stocking being knit, it being understood for instance that the welt is knitted with yarn passing through guide 1; the body of the leg is knit by yarn passing through eyes 1, 5 and 7; the ravel course by yarn 1; the heel tabs by yarns of guides 3 and 4. Yarn guides 2 and 6 are extra in the layout of the present plan, but may be used to accord with some other plan that it may be desired to employ. The means on the reciprocating driver for picking up the various carrier bands by engaging the dogs 34 thereof consist of pawls 31a. For adjusting these pawls to select the desired yarn carrier bands, a plurality of slides designated generally as a group at C, Fig. 2, are arranged at each end of the machine and at the rear part thereof. These slides are provided with projections against which controller cam slides 31j on the driver 31 abut to be slidably operated thereby to select and position the pawls 31a as in the application above mentioned by acting upon the cam shaped ends 31g of the stems of said pawls. The pawls are held in raised position so as to engage the inclined shoulders 34d on the dogs 34 by spring detents 31c.

When, however, the dog 34 is arrested by its projection 35 coming against one of the stops, as for instance *R* in Fig. 14, then the inclined shoulder 31b on the pawl 31a working against the inclines 34d and 34c on the dog will be pushed down so as to pass the dog. By this action the lower cam shaped end 31g of the stem of the pawl 31a will enter the V-shaped recess 31h of the controller slide 31j and said slide will then raise the pawl again when said slide is next operated by a projection on one of the selector slides of the group C. In said application it is also disclosed that the slides are selected and set in operative or inoperative position by cams and springs, said cams are mounted on a yarn changer shaft *b*. The group of cams, one at each end of said shaft *b* are indicated generally at 40 and 40a. This yarn changer shaft, like in said application, is operated step by step by a pawl *b* shown in

Fig. 16 and in dotted lines, Fig. 1, which engages a ratchet b^2 . The engagement of the pawl with the ratchet is controlled by shield b^5 which in turn is controlled by the main pattern mechanism shown generally at A. This control is exerted by a flexible rod housed in a tube b^7 from lever b^{12} , operated by projection b^{10} on the main pattern drum A, Fig. 1. When this shield is withdrawn from normal position through connections operated by said main pattern mechanism, the pawl, which is operated from a suitable cam b^x Fig. 16 on the main cam shaft a and lever b^3 , then can engage the ratchet and turn the yarn changer shaft, all as set forth in said application.

Certain of the selector slides C in the group at the left side of the machine, Fig. 2, control the introduction of the colored yarns. In the present layout which may be regarded only as an example, the slides C¹, C⁵ and C⁷, Fig. 8, are the ones for controlling the colors. Slide C¹ controls carrier band #1 and this carrier has mounted thereon the yarn guide eye 1 for the yarn which knits the ravel course of the stocking. Said slide C¹ in order to bring in this ravel yarn is set in position by one of the cams on the yarn changer shaft b , marked C a^1 , see Figs. 2, 4, 8, 10 and 12. This slide C¹, Fig. 4, is operated leftward by the cam and it is returned towards the right by one of the springs 42. This yarn is, say, blue in color and besides being used for knitting that part of the stocking known as the ravel courses it is also used in the present improvement for changing the color at intervals in the body of the stocking for producing the horizontal striping effect. For bringing it into action, for changing the color for striping, this selector slide C¹ is operated by the striping attachment which includes a supplemental pattern mechanism indicated generally at A¹. This consists of, say, three pattern chains, C¹¹, C¹⁵ and C¹⁷ which respectively operate the particular one of the group of levers 8 associated therewith. This supplemental pattern mechanism is located near the front of the machine as shown in Fig. 1 at the left hand side thereof. The levers are pivotally mounted on a bracket 9, attached to the main frame of the machine, which bracket also furnishes a support for the drum 10 which supports and operates the pattern chains. The drum has a ratchet wheel 11 connected therewith which is operated by a pawl 12. The pawl is held in engagement with the ratchet by a spring 13, Figs. 1, 3 and 5. The pawl is pivotally carried by an arm 14 loosely mounted on a catch bar rock shaft 15. This arm is operated in one direction by a spring 16 to retract the pawl and it is operated in the other direction by the projections 70 x on the rotary cam P driven from a gear wheel 38g as in the application above referred to, this rotary cam having to do with the tapered high splice above the heel. A stop 14a on the lever 14 abuts a hub on the cam shaft a to limit the back stroke of the pawl 12.

The operation of the pattern chains by the mechanism just described causes high links or projections thereon to operate in proper order the levers 8. These levers are connected by wires 17 with bell crank levers 18 pivotally mounted on a frame bracket 19, Figs. 3 and 4. These bell crank levers operate the selector slides C¹, C⁵, C⁷ to bring the color yarns into operation for making the stripes, by positioning their projections in proper position for operating the selector pawls on the driver. The wires 17 at a point between the supplemental pattern mechanism

and the bell crank levers pass partly around wheels 20 mounted in a rocker member or frame 21 pivoted to the main frame at 22. The position of this frame, up or down, is determined by a control cam 23, Figs. 2, 3, 8, 9 and 12, on the yarn changer shaft b , and forming one of the cams of the left hand group, Fig. 2. This cam has a high part extending for about one half of its periphery and when this is brought into action by the step by step revolution of the yarn changer shaft b it will operate upon the upper end of a lever 24 which is pivoted on the same bracket 19 with the bell crank levers 18, and coaxially therewith at 18a, Fig. 10. This lever operates a link 25 pivoted thereto at its upper end and to the frame 21 at its lower end.

This control cam 23 also determines the time at which the reciprocating pawl 12 will be effective in operating the supplemental pattern mechanism A¹ for performing the striping operations. For this purpose the lever 24 when operated by the control cam 23 will operate a rod 27 passing through a tube 28 suitably supported. The rod 27 operates the upper arm 29 of a shield lever 30 pivoted on the axis of the supplemental pattern drum 10. The lower end of this shield lever controls the engagement of the pawl 12 with its ratchet. When the rod 27 is operated by the lever 24 it will turn the shield so that the teeth of the ratchet 11 of the supplemental pattern mechanism will be exposed so as to be engaged by the pawl 12, which then will turn the pattern mechanisms and the levers 8 will be operated according to prescribed plan and disposition of the high links on the chains and the wires 17 will be operated in proper order to operate the bell crank levers 18 which will in turn, shift the slides C¹, C⁵, C⁷ to present their projections which are shown at C#1, C#5, C#7 to determine the selections of the proper pawls on the driver so as to pick up the prescribed dogs 34 for the operation of the proper yarn carrier bands.

The operation of the shield 30 by the rod 27 takes place against the tension of a spring 32. This spring through the rod 27 tends to hold the lever 24 in its raised position with its upper end against the periphery of the control cam 23, and this lever when raised raises the frame 21 to render the wires 17 slack and inoperative. This of course takes place when the low part of the control cam 23 is opposite the upper end of the lever 24. When, however, the high part of the control cam 23 comes into action upon the lever 24 two actions result. One of these is the operation of the shield 30 to bring the supplemental pattern mechanism into action by the operation of the pawl 12. The other result is the downward movement of the pivoted frame 21 by the link 25 so that the wires 17 will be rendered taut and the operation of the levers 8 of the supplemental pattern mechanism will be transmitted to the bell crank levers 18 for the selection and setting of the appropriate slides, C¹, C⁵, C⁷, of the group C for bringing into action the proper color yarns. So long as the high part of the control cam 23 presents its high part to the lever 24 the horizontal striping will go on according to the pattern prescribed because the pattern levers 8 will be operated in accordance with the disposition of the high links or projections on the several pattern chains. After the color yarns have been fed to the needles for the desired number of courses, the prescribed changes taking place by the pattern chains acting upon the levers 8, the cam 23 is

rotated to remove its high part from the lever 24 whereupon said lever will be raised by the spring 32. The supplemental pattern mechanism at the same time will be rendered inactive 5 by shifting the shield 30 to prevent the pawl 12 from operating the said mechanism and the wires 17 will be slackened by the lifting of the frame 21. The yarn changer shaft *b* makes one complete revolution, step by step, for each stocking.

10 It will be seen from the above that the supplemental pattern mechanism operates in connection with the same group of selector slides which are operated from the main pattern mechanism. One or more of the slides may be operated only by the main pattern mechanism, another 15 slide or slides may be operated only by the supplemental pattern mechanism and another slide or slides may be operated at times by the main pattern mechanism and also at times 20 by the supplemental pattern mechanism. The changes possible to be made are therefore increased by the employment of the supplemental pattern mechanism, and in respect to a given slide, say C¹, as the changes are the result of the control 25 exerted both by the main pattern mechanism and the supplemental pattern mechanism, the changes in respect to this particular slide are increased beyond those changes effected by the main pattern mechanism alone.

30 In Fig. 4 is indicated at C#1 to C#7 the projections on the several slides of the group of seven at the left of the machine for selectively operating the pawls of the driver for picking up the corresponding yarn carriers, #1 to #7, excepting in 35 this particular layout carriers #2 and #6 are idle.

While three color changes are referred to herein it will be understood that the number and plan of selection of the slides may be varied, and while only one selector slide, viz C¹, is referred to as 40 capable of being operated both by the main pattern mechanism and the supplemental pattern mechanism, the invention is not limited in this respect as the plan of operation of the slides may be changed. The principle of increasing the 45 permutations by the use of supplemental pattern mechanism controlling the same means which is controlled by the main pattern mechanism, is illustrated by slide C¹, by way of an example of what may be done with other slides. Further, 50 while all the colors are changed by selection from the group of slides at the left of the machine, the invention is not limited in this regard.

Reverting to the mechanism for rendering the wires 17 slack when the color changes have been 55 completed and the supplemental pattern mechanism is to be rendered ineffective, it will be understood that the slackening of the wires will render the supplemental pattern mechanism ineffective despite the fact that it is intended that always 60 one of the pattern levers 8 will be on a high link of the supplemental pattern chain unit. By this arrangement the chains C¹¹, C¹⁵, C¹⁷ will never present their respective low links to their levers 8 at the same time. Therefore the chains can 65 continue to perform a number of cycles during the formation of the desired pattern and maintain the prescribed slides C in action. This will enable short chains to be employed which will repeat their cycles so long as the wires 17 are taut.

70 When the prescribed color pattern has been completed it is then necessary to render all the levers 8 ineffective in further controlling the selector slides C and this is done by slackening the wires 17 and the taking over of the control of the 75 slides by the cams on the shaft *b*. The slackening

of the wires must take place at this time despite the fact that the pawl 12 is out of operation and the pattern chains are at rest, otherwise the control could not be transferred to the cams on the shaft *b* owing to one of the levers 8 still being on one of the high links. This cam set has only, say, 16 different positions in one revolution, not enough to control all the changes of yarns throughout the pattern, hence the auxiliary pattern mechanism at times exerts its control and this is accomplished as stated above with short chains repeating their cycles during the formation of the pattern.

The supplemental pattern mechanism comes into action at a time when the selector mechanism involving the slides may be said to be in open position, that is, with said slides in inoperative position in relation to the particular yarn carrier bands each is to control.

The stop mechanism for the yarn carrier bands 20 may be the same as shown in the application above mentioned and the stops are indicated in dotted lines in Fig. 2 at R^t and L^t, R_s and L_s, 25 R_a and S and other parts not shown herein are like those shown in said application.

Referring to Fig. 12, this shows the series of cams of the group C at the left of the machine. They are marked in the order in which they are located on the yarn changer shaft beginning with C_{a1} at that side of the group nearest the center 30 of the machine to C_{a7} at the outer side of the group. A collar 33 is used as a lateral bearing member for the group of cams.

The control cam 23 is adapted to be fixed on shaft *b* by a key. This cam has a lateral projection pin 35 and all the other members of this group are provided with aligning holes 36 to receive said pin whereby the relation of the cams to each other circumferentially of the shaft is determined.

The cams shown in Fig. 13 constituting the 40 group for the right hand end of the machine are likewise shown in the circumferential relation they bear to each other. In the group there are two collars 37 and 38, the former being adapted to be keyed to the shaft *b* and having an aligning 45 pin 39 to receive the other members of this group which are provided, each with an opening, for this purpose.

From the above it will be seen that the throwing out of and into operation of the supplemental pattern mechanism is controlled by the pivotally mounted frame 21 which, when in low position, tightens the wires 17 so that the operation of the levers 8 will be transmitted to the selector, and when in high position will slacken said wires to 50 release the selectors from control by the auxiliary pattern mechanism. Either the main pattern mechanism, through the connections described, involving amongst other elements the cams on the 55 yarn changer shaft, or the supplemental pattern mechanism, will be exerting control upon the selector mechanisms, so that at all times some one of the yarn feeds will be in action. The design may be varied as to color and as to width of the 60 bands making up the striped effect.

I claim:

1. In apparatus for changing yarn in a full fashioned knitting machine, a group of selector members, a shaft having cam means thereon for operating certain of said members, main pattern mechanism for giving a step by step movement to the cam shaft, supplemental pattern mechanism for operating certain of said selector members, connections between said supplemental pattern mechanism and said selector members which 70

connections are slackened to be rendered inoperative and tightened to be rendered operative, a cam on the cam shaft, and means for tightening or slackening said connections operated from said cam, substantially as described.

2. In apparatus for changing yarn in a full fashioned knitting machine, a group of selector members, a shaft having cam means thereon for operating certain of said members, main pattern mechanism for giving a step by step movement to the cam shaft, supplemental pattern mechanism for operating certain of said selector members, pawl and ratchet mechanism for operating the supplemental pattern mechanism, a shield for controlling the operation of the ratchet by the pawl, means for operating the shield for determining the times of operation of the supplemental pattern mechanism, connections from the supplemental pattern mechanism to the said selector members for operating them, said connections when slackened being inoperative and means for automatically tightening or slackening the said connections, substantially as described.

3. In apparatus for changing yarn in a full fashioned knitting machine, a group of selector members for changing the yarn, a main pattern mechanism, selector operating means controlled by the main pattern mechanism and comprising a cam shaft with cams thereon, a supplemental pattern means for controlling yarn selection comprising a plurality of comparatively short series of high and low parts with carrier means therefor, levers operated by said high and low parts, and arranged so that some one of the levers shall always be on a high part so that said carrier means with their high and low parts may perform a number of cycles for making a pattern, connections from said levers to selector members adapted to be slackened or tightened, means for operating the said carriers and means operated by a cam on the cam shaft for slackening or tightening said connections, means for controlling the carrier operating means, the control of the selector members being assumed by the cam means when the connections are slackened, substantially as described.

4. Apparatus according to claim 3 in which the means for slackening or tightening the said connection includes a shiftable member operated by the said cam, and the controlling means for the carrier operating means includes a shield for the operating pawl.

5. Yarn changer mechanism for full fashioned knitting machines and in combination selector

means for the yarn carriers, cam means for operating the selector means, main pattern mechanism for controlling the cam means, a supplemental pattern mechanism comprising carrier means having high and low parts, members operated by said high parts, connections between said members and the selector means for operating the latter, at least one or another of the said members remaining on a high part so that the supplemental pattern carrier may perform a number of cycles in forming a pattern, means for rendering the connections leading from said members to the selector means inoperative, and means for throwing the supplemental pattern mechanism out of operation, substantially as described.

6. In combination in yarn changer mechanism for full fashioned knitting machines, selector means for the yarn carriers, main pattern mechanism for controlling the selector means, a supplemental pattern mechanism comprising means having comparatively short series of high and low parts with carrier means therefor, and members operated by said high and low parts, connections between the said members and the selector means for operating the latter, at least one or another of said members being on a high part at all times, so that the supplemental pattern mechanism can perform a number of cycles in forming the pattern, and means controlled by the main pattern mechanism for throwing said connections out of operation, substantially as described.

7. Apparatus according to claim 5 in which the said connections are rendered inoperative by slackening them and are rendered operative by tightening them.

8. In combination in yarn changer mechanism for full fashioned knitting machines, selector means for the yarn carriers, main pattern mechanism for controlling the selector means, a supplemental pattern mechanism comprising means having comparatively short series of high and low parts with carrier means therefor, and members operated by said high and low parts, connections between the said members and the selector means for operating the latter, at least one or another of said members remaining on a high part, so that the supplemental pattern mechanism can perform a number of cycles in forming the pattern, and means for automatically throwing said connections out of operation, said automatic means including a rocker member, a cam and a connection between said cam and rocker member.

KENNETH HOWIE.
